UNITED STATES PATENT OFFICE.

DUMITRU GOLOGAN, OF NEWARK, NEW JERSEY.

PROTECTOR MEANS OR GUARD FOR CIGARETTE HOLDERS.

Application filed April 1, 1924. Serial No. 703,351.

This invention relates, generally, to improvements in smokers' articles; and, the present invention has reference, more particularly, to improvements in cigarette holders, with a view of providing the holder and the lighted cigarette carried by the holder, with means, in the form of a guard, which will prevent the ashes and sparks from dropping upon the garments of the 5 smoker, or when used in the home, from dropping upon the floor, carpets, or rugs, as the case may be.

The present invention, therefore, has for its principal object, the provision of a 15 novel and simply constructed protector-means for a cigarette-holder and the lighted cigarette carried by the holder, which will not interfere with the smoking of the cigarette, and which serves to collect the ashes 20 from the cigarette, as the latter is being consumed, so as to prevent the ashes from dropping upon the garments of the smoker, or when used in the home, from dropping upon the floor, carpets, rugs, or the like; 25 and, furthermore, to prevent the ashes and sparks from flying about, especially, when smoking in an automobile.

Other objects of the present invention not at this time more particularly enumerated 30 will be clearly understood from the following detailed description of the present invention.

With the various objects of the present invention in view, the said invention consists, primarily, in the novel protector-means 35 or guard for cigarette holders hereinafter set forth; and, the said invention consists, furthermore, in the novel arrangements and combinations of the various devices and parts, as well as in the details of the construction of the said parts, all of which will 40 be more fully described in the following specification, and then finally embodied in the clauses of the claim which are appended 45 to and which form an essential part of the said specification.

The invention is illustrated in the accompanying drawings, in which:—

Figure 1 is a view, illustrative of the use 50 of the protector-means or guard with a cigarette-holder and a cigarette, when used by a person smoking and seated in an automobile.

Figure 2 is a view, made on an enlarged 55 scale, of the combined cigarette-holder and the protector-means or guard, showing one

embodiment of the principles of the present invention; Figure 3 is a longitudinal vertical section of the cigarette-holder and the protector-means or guard; and Figure 4 is 60 a horizontal representation of the said cigarette-holder and the protector-means or guard, said view showing in connection therewith and in elevation, a lighted cigarette and a portion of the ashes from the 65 cigarette collected in said protector-means or guard.

Figure 5 is a vertical cross-section, taken on line 5—5 in said Figure 2; Figure 6 is 70 an end-view of the protector-means or guard, said view being made on an enlarged scale; Figure 7 is a cross-section of the protector-means or guard, said section being taken on line 7—7 in said Figure 2, and said view also being made on an enlarged scale; 75 and Figure 8 is a vertical section, taken on line 8—8 in Figure 6, looking in the direction of the arrow α in said figure. Figure 9 is a perspective view of the wire-mesh gauze protector-means or guard, showing 80 its one end-portion slitted to provide tabs, adapted to be folded so as to provide the re-enforced closed end of the guard, represented in said Figure 6 of the drawings.

Similar characters of reference are 85 employed in all of the above described views, to indicate corresponding parts.

Referring now to the said figures of the drawings, the reference-character 1 indicates any usual cigarette-holder, of which 2 is the mouth-piece, 3 is the receiving end or socket of the same, into which one end of a cigarette 4 is adapted to be forced and held, as shown in Figure 4 of the drawings, and 5 is the usual smoke-conducting duct 90 of the cigarette-holder. The outer surface-portion surrounding the receiving end 3 of the cigarette-holder is usually cut away, as shown in the accompanying drawings, so as to provide an annular recess, as 6, onto 95 which is sprung, in separable retaining or holding engagement, a series of spring-fingers, as 8, which extend from one of the marginal edges, as 9, of a suitably formed ring or ferrule 7. This ring or ferrule is 100 also preferably provided with suitably disposed perforations 10, for proper ventilation, to prevent the protector-means or guard from becoming overheated, and also 105 to permit of a perfect suction through the cigarette-holder, when smoking.

The above-mentioned protector-means or

guard is indicated by the reference-character 11, and has its end-portion 12 surmounted by the said ring or ferrule 7, and permanently affixed in said ring or ferrule by 5 means of solder, or otherwise.

In practice, this protector-means or guard 11 is made of a very fine wire-mesh or gauze, being suitably rolled so as to provide a tubular element, the overlapping and longitudinally extending edge-portions 13 being suitably secured together by means of solder, or otherwise.

At its opposite end-portion 14 the tube thus produced is suitably slitted, as at 15, 15 so as to provide a number of tabs 16 which are bent over at right angles to the cylindrical surface of the tube, and are suitably secured together in their overlapping relation, substantially as indicated in Figures 6 20 and 8 of the drawings, by means of solder or otherwise, and whereby the end-portion of the protector-means or guard is suitably re-enforced and strengthened against collapse when taking hold of the same for removal from or for forcing its ferrule-mounted end upon the depressed or recessed portion 6 of the cigarette-holder, as will be clearly evident.

Having in the foregoing description set 30 forth one general construction of protector-means or guard for cigarette-holders, I will now briefly set forth its use with the holder for attaching and lighting the cigarette, and for storing the ashes and arresting any 35 sparks, within the protector-means or guard, while smoking.

To attach the cigarette to the holder, the protector-means or guard, at its ferrule-mounted end, is withdrawn from its retained 40 connection with the cigarette-holder. The cigarette is thereupon attached to the holder and lighted in precisely the same manner as

is now ordinarily done. After the cigarette has been lighted, the tubular protector-means or guard is passed over the lighted 45 end of the cigarette and its ring or ferrule brought into holding engagement with the end-portion of the cigarette-holder, in the manner hereinabove described, and as illustrated in Figures 2, 3 and 4 of the drawings. When the several devices are thus assembled, the wire-mesh or gauze protector-means or guard does not in the least interfere with the smoking of the cigarette, and serves as a collector of the ashes and sparks 50 55 from the burning cigarette, as will be clearly evident.

Of course, I am aware that my present invention is capable of changes in the construction of the several devices without departing from the scope of the present invention as set forth in the foregoing specification. Hence, I do not limit my present invention to the exact arrangements and combinations of the various devices and 60 parts as described in the said specification, nor do I confine myself to the exact details of the construction of the said parts as illustrated in the accompanying drawings.

I claim:—

The combination with a cigarette holder, of a guard member comprising a tube formed of wire mesh, said tube having one end open and adapted to be removably connected to the cigarette holder, the tube being provided at its opposite end with a plurality of triangular tabs bent at right angles to the longitudinal axis of the tube and forming a closure for the tube at said end.

In testimony, that I claim the invention 80 set forth above I have hereunto set my hand this 27th day of March, 1924.

DUMITRU GOLOGAN.
